CLAIM

The ornamental design of a pneumatic tool, as shown and described.

DESCRIPTION

FIG. 1 is an isometric view of a pneumatic tool showing our design;

FIG. 2 is a top view of FIG. 1;

FIG. 3 is a bottom view of FIG. 1;

FIG. 4 is a rear elevational view of FIG. 1;

FIG. 5 is a front elevational view of FIG. 1;

FIG. 6 is a right side view of FIG. 1; and,

FIG. 7 is a left side view of FIG. 1.

The structural features depicted by means of broken lines in the drawing have been shown for illustrative purposes only and form no part of the claimed design.
